UNITED STATES PATENT OFFICE

141,915

DESIGN FOR A WASHER FOR MEAT PRODUCTS OR THE LIKE

Frank J. Bilek, Chicago, Ill., assignor to The Globe Company, Chicago, Ill., a corporation of Illinois

Application September 25, 1944, Serial No. 115,452

Term of patent 14 years

(Cl. D48—1)

To all whom it may concern:

Be it known that I, Frank J. Bilek, a citizen of the United States, residing at Chicago, in the county of Cook and State of Illinois, have invented a new, original, and ornamental Design for a Washer for Meat Products or the like, of which the following is a specification, reference being had to the accompanying drawings forming a part thereof.

Fig. 1 is an end elevational view of a washer for meat products or the like embodying my new design;

Fig. 2 is a similar view of the washer shown in Fig. 1 with the lid in raised position;

Fig. 3 is a front elevational view of the washer shown in Fig. 1; and

Fig. 4 is a top plan view thereof.

The characterizing features of new design reside in the portions shown in full lines.

I claim:

The ornamental design for a washer for meat products or the like, substantially as shown and described.

FRANK J. BILEK.
